(57) **CLAIM**

(21) Appl. No.: **29/263,265**

The ornamental design for an apparatus for volumetric enumeration of blood cells, as shown and described.

(22) Filed: **Jul. 20, 2006**

DESCRIPTION

(51) **LOC (8) Cl. 10-04**

FIG. 1 is a top, front, and side perspective view of an apparatus for volumetric enumeration of blood cells showing my new design.

(52) **U.S. Cl. D10/97; D10/81; D24/186;**

FIG. 2 is a bottom, rear, and side perspective view thereof.

D24/232

FIG. 3 is a front elevational view thereof.

(58) **Field of Classification Search** D10/46,

FIG. 4 is a right side elevational view thereof.

D10/81, 97; D24/216, 224, 232, 233, 234,
D24/186; 435/5, 6, 7, 24, 288.3, 287.2

FIG. 5 is a rear elevational view thereof.

See application file for complete search history.

FIG. 6 is a left side elevational view thereof.

(56) **References Cited**

FIG. 7 is a top plan view thereof; and,

U.S. PATENT DOCUMENTS

FIG. 8 is a bottom plan view thereof.
